United States Patent

Des. 237,487
Patented Nov. 4, 1975

237,487

LABEL OR SIMILAR ARTICLE

Edward Parker, 307 H St. NW.,
Washington, D.C. 20001

Filed May 20, 1974, Ser. No. 471,574

Term of patent 14 years

Int. Cl. D19—08; D11—03

U.S. Cl. D19—16

The figure is a front elevational view of a label or similar article showing my new design, it being understood that the label has insubstantial thickness and that the rear is plain.

I claim:

The ornamental design for a label or similar article, as shown and described.
